Patented Oct. 5, 1920.

2 SHEETS—SHEET 2.

UNITED STATES PATENT OFFICE.

CLAYTON ST. JOHN, OF MIAMISBURG, OHIO.

GOVERNOR-VALVE CONTROLLER FOR STEAM-ENGINES.

1,354,703.

Specification of Letters Patent.

Patented Oct. 5, 1920.

Application filed January 26, 1920. Serial No. 354,046.

To all whom it may concern;

Be it known that I, CLAYTON ST. JOHN, a citizen of the United States, residing at Miamisburg, in the county of Montgomery and State of Ohio, have invented certain new and useful Improvements in Governor-Valve Controllers for Steam-Engines; and I do declare the following to be a full, clear, and exact description of the invention, such 10 as will enable others skilled in the art to which it appertains to make and use the same.

This invention relates to valve-controlling devices, and more specifically to an improved governor valve-controller for steam engines, and comprises improvements on a valve-controlling mechanism similar to that disclosed in the Patent No. 979,289, issued to S. S. Hall on Dec. 20, 1910.

20 An object of this invention is to supplement the emergency-controlled connection of said mechanism by another emergency-controlled connection, and thereby additionally safe-guarding the speed of the engine.

Another object is to provide an improved speed-controlled attachment which is exceedingly simple of construction and operation, easily attachable to an engine and 30 to a machine driven by the engine, is positive and instantaneous in its action, adjustable to operate at different maximum speeds, and adjustable to operate in connection with controlling and controlled shafts 35 spaced various distances from one another.

Other objects and advantages are pointed out or implied in the following details of description in connection with the accompanying drawings in which:

40 Figure 1 is a perspective view illustrating a portion of an engine, a portion of a machine driven by the engine and, in turn, driving the governor of the engine, and an emergency-controlled valve-controlling 45 mechanism including the present invention.

Fig. 2 is a detail sectional view, the section being taken substantially along the line 2-2 of Fig. 1.

Fig. 3 is an enlarged detail view illustrating a portion of the mechanism which controls the governor-valve.

Fig. 4 is a detail sectional view, the section being taken substantially along the line 4-4 of Fig. 3.

55 Referring to these drawings in detail, in which similar reference characters corre-

spond with similar parts throughout the several views, and in which the valve chamber 1, governor 2, and machine 3 are of well known construction, the invention consists in the provision of an attachable trip-extension 4 and an attachable rotary tripping device 5 which will be described in detail in connection with the governor-valve-stem 6 and means for controlling the latter 60 in opposition to the action of the governor 2. These means will now be specifically described in connection with the controlling device 4-5 as follows:

The governor frame 7 is formed with 70 bearings in which a well known form of valve-controlling shaft 8 is mounted for rotary or rocking movement, this shaft being provided with an arm 9 which engages between a pair of shoulders 10 of the valve-stem 6 in such relation that the latter is normally held up in the position for holding the valve (not shown) open. The shaft 8 is, in turn, held in this valve-supporting position by means of a torsional spring 11 75 which extends helically around the shaft 8 and has one end connected to the shaft as indicated in Fig. 2, the other end being connected to a ratchet-wheel 12 through the medium of a polygonal boss 13, the latter 80 being integral with the ratchet-wheel, and this member 12-13 being journaled on the shaft 8 and adapted to be rotated independently of the latter. A pawl 14 is united with a shaft 15, and an arm 16 extends 85 laterally from the shaft and constitutes a trip-arm which is operable to disengage the pawl 14 from the ratchet wheel 12, and the trip-extension or tubular attachment 4 is adjustably secured on the arm 16 by means 90 of a set screw 17 or by other appropriate means. The lower end of the tubular member 4 is closed by means of a solid head 18 which is preferably rectangular, and this head stands in the path of a pusher 19 which 95 is pivotally mounted at 20 on a disk 21, the latter being secured by any appropriate means on a portion of a shaft 22 of the machine 3. A spring 24 has one end connected to the pusher 19, its other end being connected to a screw threaded member 25 which is provided with a nut 26, the latter being 100 co-operative with the member 25 for tensioning the spring 24 for a purpose which will presently appear. It is obvious that the 105 rotary tripping device 5 comprises the elements 19 to 26 inclusive, and in addition,

a strap or yoke 27 may be employed for providing a guide and a pair of stops for controlling movement of the pusher 19.

The machine 3 is provided with a pulley 5 28 on the shaft 22, and a belt 29 connects this pulley with a pulley 30 on a shaft 31. This latter shaft coacts with the governor-actuated shaft 32 through the medium of a chain 33 and sprocket wheels on the respective shafts 31 and 32. The machine 3 may be driven by the engine through any appropriate means (not shown) so that the speed of the machine is controlled by the speed of the engine, and on the other hand, the speed of the engine is controlled by the speed of the machine 3 through the medium of the governor-actuating shaft 32 and the contiguous transmission elements. Therefore, the governor 2 controls the speed of the engine 15 and machine under normal conditions, but in the event of the breaking of a belt or driving chain which connects the machine to the engine, the latter will exceed its safe speed limit, and the prior patent 20 (previously referred to) provides for such contingency by employing an idler 34 which is carried by the main driving chain 35 and by an arm 36, the latter being pivotally mounted on the governor frame 7 and carrying a cam 37 which is movable by the arm 36 into contact with the trip-extension 4. Therefore, in the event the belt or chain 35 breaks, the arm 36 swings downward on its pivot, moving the cam 37 against the trip-extension 4 and causing shaft 15 to swing the pawl 14 out of engagement with the ratchet 12. Now, assuming that the ratchet has previously been turned forward in the direction of the arrow, (so as to tension the spring 11 and cause the arm 9 to hold the valve stem 6 up), the removal of the pawl 14 from its engagement with the ratchet-wheel effects the release of the latter and permits it to relax its tensioning effect upon the spring 11. Moreover, when the pawl 14 is released, the action of the spring suddenly rotates the ratchet backward, and this momentum combines with the weight of the valve-stem 6 to lower the latter so as to close the valve in the chamber 1. Moreover, assuming that the governor is operating when the ratchet-wheel 12 is released, the resistance of the spring 11 in opposition to the governor 2 is released, and the governor 50 assists in closing the valve or reducing its outlet to such an extent that the racing of the engine and machine is checked.

Any appropriate means may be provided for securing the valve in its closing position, after being closed by the means previously specified, and in this connection, the previously known device which is employed in connection with this attachment 4 may be briefly described as follows:

65 A radially extending arm 38 is united

with the shaft 8 and is provided with a shoulder 39 which stands in the path of the attachment 4, and when the latter is moved forward by means of the cam 37, it moves against the shoulder 39 and prevents 70 the latter from returning to its normal position, thereby coacting with the shaft 8 and arm 9 in holding the valve-stem down. In this connection, it should be understood that the attachment 4 is secured in its engagement with the shoulder 39 by means of the cam 37.

From the foregoing description, it will be seen that the previously known devices, mentioned herein, are effective only in the 80 event of the breaking of a certain belt or transmission member 35, but if the engine races from any other cause, such as by the breaking of another belt, the breaking of a shaft, or the loosening of a pulley on the 85 shaft, the arm 36 cannot swing down to operate the valve-controlling mechanism. Therefore, to meet the contingencies above mentioned, the present invention provides the coöperating devices 4 and 5, the first 90 being attachable to and adjustable on the arm 16, and the second being attachable to and adjustable on the shaft 22. The adjustment of the disk 21 of the device 5 along the shaft 22 brings the member 19 in 95 position to move into the path of the member 4 provided the latter is properly adjusted on the arm 16; but it should be understood that the adjustment of the spring 24 also determines whether or not the member 19 moves out sufficiently far, at a given rate of speed, to strike and push the member 4. These relative adjustments are important because it is not always possible to set the engine and the machine which it 100 drives in such position relative to one another that the member 19 will strike the member 14 without adjustment of one or the other of these members. Moreover, by adjusting the member 4 farther away from 110 the member 19, a greater speed is required to cause the latter to move by centrifugal force into contact with the member 4; and moreover, by increasing the tension of the spring 24, a greater speed is required to 115 throw the member 19 out into position for pushing the member 4.

It is not intended to limit this invention to the exact details of construction and arrangement shown and described, but changes 120 may be made within the scope or inventive ideas as implied and claimed.

What is claimed as my invention is:

1. The combination with an engine and an engine-controlling device, the latter including a governor-controlled valve-stem and means engaged with said valve-stem to control the valve-stem in opposition to said governor, said means including a trip-arm, of an extension attachable to said trip arm, 130

a machine operable by said engine and including a rotary shaft, and a rotary tripping device attachable to said rotary shaft so as to be rotated with the latter, said rotary tripping device including a pivotally mounted spring-held pusher adapted to be thrown by centrifugal force into a position to engage and push said extension of the trip-arm for actuating the latter.

10 2. The combination with an engine and an engine-controlling device, the latter including a governor-controlled valve-stem and means engaged with said valve-stem to control the valve-stem in opposition to said 15 governor, said means including a trip-arm, of a tubular trip-extension attachable to and adjustable longitudinally of said arm for extending the latter, said tubular trip-extension having the free end portion of 20 said arm seated therein and being provided with means to secure it in its different adjustments, and a rotary tripping device operable by said engine and including a centrifugally operable pusher to engage with 25 and actuate said trip extension.

3. The combination of a valve-stem, a shaft, a trip-arm on said shaft and operable by the latter to control a valve through the medium of said valve-stem, a ratchet-wheel mounted for rotation on and independently 30 of said shaft, a spring connecting said shaft to said ratchet-wheel, a pawl engaged with said ratchet-wheel, an arm connected to said pawl and operable to actuate the latter, an adjustable trip-extension on said arm, and 35 a rotary tripping device including a pusher mounted for outward movement into a position to engage with and push the free end of said adjustable extension, said pusher being operable by centrifugal force so that 40 said outward movement varies according to the variations of speed of said rotary tripping device, whereby the adjustments of said trip-extension provide for its engagement by said pusher at various maximum 45 speeds of said rotary tripping device.

In testimony whereof I have hereunto set my hand.

CLAYTON ST. JOHN.
